[57] **CLAIM**

The ornamental design for a typewriter feature attachment, as shown and described.

DESCRIPTION

FIG. 1 is a left rear perspective view of the typewriter feature attachment, showing my new design;

FIG. 2 is a rear elevational view thereof;

FIG. 3 is a top plan view thereof;

FIG. 4 is a left side elevational view thereof;

FIG. 5 is a right side elevational view thereof;

FIG. 6 is a bottom plan view thereof; and

FIG. 7 is a front elevational view thereof.

The broken line showing of environmental structure is for illustrative purposes only and forms no part of the claimed design.

FIG. 1

FIG. 2

FIG. 3

FIG. 4

FIG. 5

FIG. 6

FIG. 7
